VIBRATING APPARATUS UTILIZING A LIQUID
AS ECCENTRIC WEIGHT MEANS

George D. Becker, Wauwatosa, Wis., assignor to Allis-Chalmers Manufacturing Company, Milwaukee, Wis.

Application October 4, 1954, Serial No. 459,940

4 Claims. (Cl. 74—87)

The present invention relates generally to vibrating apparatus in which a centrifugal force is created and utilized to impart a vibratory movement to the apparatus.

In vibrating apparatus of this type a rotatable shaft is journaled in a resiliently mounted body such as a vibrating screen, or a vibrating ball mill, and eccentrically positioned weight means or masses associated with the shaft create a centrifugal force when the shaft is rotated. If the eccentric weights are rigidly connected to the shaft the centrifugal force is transmitted to the vibratable body of the apparatus through the bearings in which the shaft is journaled.

The specific type of such apparatus to which the present invention pertains is apparatus in which the shaft is provided with means for causing the eccentric weights to move in a circular path but the eccentric weights are not rigidly connected to the shaft. Prior art apparatus of this type includes a cylindrically shaped casing attached to the vibratable body and arranged concentrically of the shaft. The cylindrical casing defines an enclosed chamber and disposed in the chamber are eccentrically positioned weights which may be balls or rollers. Attached to the shaft is an impeller which, upon rotation of the shaft, engages the balls or rollers so as to cause the balls or rollers to move in a circular path. The centrifugal force acting on the balls or rollers is transmitted through the cylindrical casing to the vibratable body of the apparatus and a vibratory motion is thereby imparted to the vibratable body. No part of the centrifugal force created by the movement of the balls or rollers in a circular path is transmitted through the bearings in which the shaft is journaled.

With prior art vibratory apparatus of the type referred to the balls or rollers comprising the eccentrically positioned weights are caused by centrifugal force to engage the internal surface of the cylindrical casing with great force. The friction thereby incurred is appreciable and the resulting heat generated and the resulting wear to the balls or rollers represent serious disadvantage. Noisiness in operation is another disadvantage of the apparatus.

A primary object of the present invention is to provide a new and improved vibratory apparatus of the type referred to in which the friction between the eccentrically positioned weight means and the surface which causes the weight means to travel in a circular path is substantially reduced. With reduced friction the wear on the weight means and the heat generated are correspondingly less and these are other objects of the invention.

Another object of the invention is to provide vibratory apparatus of the type referred to in which the amplitude of vibration thereof can be varied easily and accurately.

Another object is to provide vibratory apparatus of the type referred to having eccentrically positioned weight means which cooperate quietly with the surface which restrains and causes the weight means to travel in a circular path.

Other objects will become apparent from the following

detailed description of the invention and the accompanying drawing which shows one embodiment of the invention.

In the drawing:

5 Fig. 1 is a vertical sectional view through the longitudinal axis of a vibrating ball mill embodying the present invention; and

Fig. 2 is a cross sectional view taken on line II—II of Fig. 1.

10 Referring to Fig. 1, a vibratable body which is illustrated as a cylindrically shaped container 10 is shown suspended by cables 11 from a stationary overhead supporting structure 12. Resilient means such as springs 13 are provided between cables 11 and supporting structure 12 to allow container 10 to have a vibrational movement relative to supporting structure 12.

Container 10 has annularly shaped end walls 14 and 15. Material inlet and discharge openings 16 and 17 are provided at opposite ends of container 10. Also pro-

20 vided at opposite ends of container 10 are coaxially arranged bearing housings 20 and 21 which are attached to end walls 14 and 15 as by welding. Bearings 22 and 23, in which a shaft 24 is journaled, are mounted in bearing housings 20 and 21, the axis of shaft 24 being coincident with the longitudinal axis of container 10. Bearing

25 housings 20 and 21 are provided with outward walls 30 and 31 and inward walls 32 and 33. Suitable sealing means 34, 35, 36 and 37 may be provided between shaft 24 and bearing housing walls 30, 31, 32 and 33, respectively.

30 Surrounding shaft 24 and extending between container end walls 14 and 15 is a cylindrically shaped casing or tube 40. As illustrated herein tube 40, in conjunction with bearing housing walls 32 and 33, shaft 24 and sealing means 36 and 37, comprise casing means that defines a fluid tight chamber 41 which is coaxial relative to the axis of shaft 24.

35 An impeller 42 is disposed in chamber 41 and is attached as by keying to shaft 24 for rotation therewith.

40 A predetermined quantity or mass of a liquid, which serves as an eccentrically positioned weight 43, is disposed in fluid tight chamber 41. Rotation of shaft 24 causes impeller 42 to impel the eccentrically positioned mass of liquid 43 in a circular path about the axis of shaft 24 within chamber 41. The centrifugal force acting on the mass of liquid 43 is transmitted radially through tube 40 to the vibratable container 10 and a vibratory motion is thereby imparted to container 10.

45 Impeller 42 may be of various shapes within the scope of the invention. As illustrated herein impeller 42 has a generally cylindrical shape with an axially extending trough or channel 44 formed in the external surface there-

50 of. The liquid material 43 is disposed in the trough 44 and upon rotation of impeller 42 the liquid material 43 in trough 44 is caused to move in a circular path. The surface which defines trough 44 extends in a longitudinal direction into closely spaced relation to the inner walls 32 and 33 of bearing housings 20 and 21. The leading and trailing surface portions of the surface which defines trough 44 extend in a generally radial direction into closely spaced relation to the inner surface of tube 40.

55 Impeller 42 may be balanced in a variety of ways and as illustrated herein the impeller is balanced by the formation of an enclosed cavity 45 in impeller 42 which is positioned diametrically opposite trough 44. The balanc-

60 ing of impeller 42 prevents vibrational forces from being transmitted from shaft 24 to bearings 22 and 23.

65 Mercury, by virtue of its large specific gravity, is a very satisfactory liquid for use with the apparatus described because the space requirement for accommodating it in chamber 41 is correspondingly small.

70 The exact quantity of liquid to be used for a particular

installation embodying the invention is of course dependent upon the amplitude of vibration desired. A particular advantage of the invention in this respect is that the amplitude of vibration of the apparatus may be varied easily and accurately by changing the quantity of liquid disposed in the trough 44 of impeller 42.

During operation of the mechanism the centrifugal force acting on the eccentrically disposed mass of liquid 43 in trough 44 causes the liquid to be forced radially outwardly so that there is no tendency for the liquid to escape through sealing means 34, 35, 36 and 37 while impeller 42 is rotating. It is therefore contemplated that an operative mechanism can be constructed in which the sealing means are omitted.

A motor 50 mounted on a stationary support 51 is provided for driving shaft 24 of the mill. As the container 10 of the mill is vibratable relative to motor 50, a flexible coupling 52 is provided between shaft 53 of the motor and shaft 24 of the mill.

While only one embodiment of the invention is described and illustrated herein, it is to be understood other embodiments and modifications of the invention may be made and used without departing from the spirit and scope of the invention as set forth in the appended claims.

It is claimed and desired to secure by Letters Patent:

1. Vibrating apparatus comprising a vibratable body adapted to be resiliently mounted for vibrational movement relative to a stationary support, a cylinder attached to said vibratable body, bearing means operably attached to said vibratable body, a rotatable shaft journaled in said bearings, a shaft disposed coaxially within said cylinder and journaled in said bearings for rotation relative to said cylinder, means disposed within said cylinder freely movable relative to said shaft and said cylinder, and an impeller disposed within said cylinder and attached to said shaft for pushing said means around the inner peripheral surface of said cylinder to impart a vibratory movement to said vibratable body.

2. Vibrating apparatus comprising a vibratable body adapted to be resiliently mounted for vibrational movement relative to a stationary support, a cylinder attached to said vibratable body, bearing means operably attached to said vibratable body, a rotatable shaft journaled in said bearings, a shaft being disposed coaxially within said cylinder and journaled in said bearings for rotation relative to said cylinder, a liquid material disposed in said cylinder, sealing means disposed between said cylinder and said shaft to confine said liquid within said cylinder, and an impeller disposed within said cylinder and at-

tached to said shaft for pushing said liquid material around the inner peripheral surface of said cylinder to impart a vibratory movement to said vibratable body.

3. Vibrating apparatus comprising a vibratable body adapted to be resiliently mounted for vibrational movement relative to a stationary support, a cylinder attached to said vibratable body, bearing means operably attached to said vibratable body, a rotatable shaft journaled in said bearings, a shaft disposed coaxially within said cylinder and journaled in said bearings for rotation relative to said cylinder, a portion of mercury disposed in said cylinder, sealing means disposed between said cylinder and said shaft to confine said mercury within said cylinder, and an impeller disposed within said cylinder and attached to said shaft for pushing said mercury around the inner peripheral surface of said cylinder to impart a vibratory movement to said vibratable body.

4. Vibrating apparatus comprising a vibratable body adapted to be resiliently mounted for vibrational movement relative to a stationary support, a cylinder attached to said vibratable body, bearing means operably attached to said vibratable body, a rotatable shaft journaled in said bearings, a shaft being disposed coaxially within said cylinder and journaled in said bearings for rotation relative to said cylinder, a liquid material disposed in said cylinder, sealing means disposed between said cylinder and said shaft to enclose said cylinder and confine said liquid within said cylinder, and an impeller disposed within said cylinder and attached to said shaft for pushing said liquid material around the inner peripheral surface of said cylinder to impart a vibratory movement to said vibratable body, said impeller having a surface portion for engaging said liquid material which extends radially and longitudinally of said shaft into closely spaced sealing relation to the internal surfaces of said enclosed cylinder.
